UNITED STATES PATENT OFFICE

ADOLPH W. RYBECK, OF MILWAUKEE, WISCONSIN, ASSIGNOR TO T. L. SMITH COMPANY, OF MILWAUKEE, WISCONSIN, A CORPORATION OF WISCONSIN

MATERIAL-HANDLING MACHINE

Application filed December 7, 1927. Serial No. 238,323.

This invention relates to certain new and useful improvements in material handling machines and refers more particularly to the means for operating the discharge chutes commonly employed in connection with concrete mixers of the rotating drum type and adapted to have their inner ends projected upwardly into the path of the batch whereby the same is discharged from the drum, the chute having a normal inactive position with its discharge end inclined upwardly and its receiving end adjacent the drum discharge opening and out of the path of the batch.

5 10 15 20

Difficulty has been experienced in the past, particularly with concrete mixers of smaller capacities, wherein the chute is manually operated to and from its operative position, in providing means whereby the chute may be quickly and easily manipulated, and this invention has as an object the provision of improved chute operating means whereby the same may be readily manipulated with the exertion of a minimum of energy.

A more specific object of this invention resides in the provision of an improved arrangement of levers whereby the chute is quickly operated with a minimum of energy and in which the mechanical advantage increases proportionally as the chute receiving 25 30 35 40

end is moved into the path of the batch within the drum.

And a still further object of this invention resides in the provision of an improved appliance of the character described which is of very simple construction thus increasing 35 40 45 50 55

its reliability and eliminating the necessity of frequent repairs and which may be readily applied to machines at the time of manufacture or to the machines now in use.

With the above and other objects in view which will appear as the description proceeds, my invention resides in the novel construction, combination and arrangement of parts substantially as hereinafter described 40 45 50 55 60 65 70 75 80 85 90 95

and more particularly defined by the appended claims, it being understood that such changes in the precise embodiment of the herein disclosed invention may be made as come within the scope of the claims.

In the accompanying drawings, I have il-

lustrated one complete example of the physical embodiment of my invention constructed according to the best mode I have so far devised for the practical application of the principles thereof, and in which:

Figure 1 is a side, elevational view of a material mixing machine equipped with a chute operating means embodying my invention;

Figure 2 is a view, partly in section and partly in elevation, taken through Figure 1 on the plane of the line 2—2;

Figure 3 is a fragmentary, side elevational view, with parts broken away, on the plane of the line 3—3 of Figure 2; and

Figure 4 is a view, partly in section and partly in elevation, taken through Figure 2 on the plane of the line 4—4.

Referring now more particularly to the accompanying drawings, in which like numerals designate like parts throughout the several views, 5 designates a concrete mixing machine of conventional construction having a suitable frame structure including uprights and braces 6 of angle iron or other structure, and 7 a mixing drum rotatably mounted within the frame and adapted to have materials fed thereto by a loading skip or other means 8 which are discharged therefrom after they have become thoroughly mixed, by means of a chute 9. The chute is preferably of channel or trough shape carried by a medial bracket or arm 10 preferably of arcuate shape with its upper end fixed to a shaft 11 journaled in bearings 12 fixed to certain of the forward supports 6. The chute normally reposes in the position illustrated in Figures 1 and 3 with its outer discharge end 9' elevated and its inner receiving end 9'' downward and just inwardly of the drum discharge opening, not shown, so that the same is out of the path of the batch which is being mixed.

When it is desired to discharge a batch from the drum, the chute is swung in a counter-clockwise direction with respect to Figures 1 and 3, elevating and shifting its receiving end into the drum to intercept the batch so that it falls into the chute and is discharged either directly on the ground, or into

suitable receptacles placed under the chute discharge end 9'. Heretofore, the chute has been manipulated by means of a lever fixed to the shaft and operated directly from a 5 crank fixed to an operating shaft, and difficulty has been experienced with such a construction due to the force required to swing the chute receiving end into the path of the batch within the drum, as the batch, in addition to its great weight, has added thereto the 10 force imparted by its being thrown about within the drum, as will be apparent. The structure now about to be described assures the quick movement of the chute to either of its positions with a minimum of energy and 15 at the same time compacts the mechanism within a small area so as not to be cumbersome.

The shaft 11 has one end extended beyond 20 one bearing 12 to which one end of a crank arm or lever 13 is keyed or otherwise fixed, a link 14 having one end pivoted to the outer end of the lever, as at 15, and its other end pivotally connected with a lateral projection 25 or lug 16 of a lever 17, as at 18. The lever 17 is swingingly mounted on a shaft 19 supported in a bearing bracket structure 20 secured to the uprights by a suitable channel beam 21. Also formed on the outer end of the lever 17 30 and directed laterally in a direction opposite to the projection 16, is a projection 22 to which one end of a link 23 is pivoted, as at 24, to the outer end of which is pivoted, as at 25, to the outer end of a crank or lever 26 having 35 its inner end fixed to a shaft 27 journaled in the bearing portion 28 at the outer end of the bracket 20, the shaft 27 having a large bevel gear 29 fixed thereto with which a pinion 30, fixed on a shaft 31, meshes. The shaft 40 31 may be either power or manually operated and is preferably journaled in bearings 32 supported from the framework of the mixer and in the present instance its forward end extends beyond the framework to receive a 45 suitable operating wheel 33.

When the chute 9 is in its inoperative position illustrated in Figures 1 and 3, its weight 50 normally tends to swing the same downwardly to extend its receiving end into the path of the batch within the drum, but it is held in check as the end of link 14 connected with the lever 17 is positioned beyond a line drawn through the centers of the pivots 15 and 19 so that upward movement of the outer end 55 of the lever 17 is consequently checked. However, when it is desired to move the chute to its operative position indicated by the full lines in Figure 4, shaft 31 is rotated by the hand wheel or other means 33 in a direction to 60 impart a counterclockwise rotation to the beveled gear 29, and consequently the shaft 27. As a result, the outer end of the crank lever 26 moves to the right and upwardly with respect to Figure 3, swinging the lever 65 17 on its pivot in a corresponding direction

and moving the link 14 beyond its center at which time the weight of the chute assists in its movement to reduce the amount of energy necessary to rotate the shaft 31 at the point the mechanical advantage of the leverage of 70 the drive is at a minimum.

As the chute approaches the intermediate dotted line position illustrated in Figure 4, its end 9" intercepts the batch within the drum 7 and applies the maximum load by reason of the weight of the batch accumulating 75 thereon and the momentum of its fall, and as the chute reaches this position, the mechanical advantage of the leverage has increased to nearly its maximum, as shown by 80 the dotted lines in Figure 4, the lever 26 has at that point a straight lift on the lever 13. As the shaft 31 continues to be rotated, the chute and the levers continue on to their full line positions illustrated in Figure 4, the mechanical advantage of the leverage steadily 85 increasing almost up to the end of the movement which is a few degrees further than the position depicted by the full lines of Figure 4, and when the end of movement has been 90 reached the center of pivot 18 will have passed beyond an imaginary line drawn through the centers 19 and 15, locking the parts in discharging position.

Thus it will be apparent that the arrangement of the leverage is such that the chute is locked in both positions, that a great lifting force is obtained from a device compacted within a small area and that an increased efficiency in the operation is accomplished. 95

What I claim as my invention is:

1. In a material mixing machine including a discharge chute and means mounting the same for movement from an inoperative position with its receiving end lowermost, said chute tending to move by gravity to elevate and shift its receiving end inwardly, means for swinging the chute from its inoperative position to an operative position with its receiving end uppermost and inward of a line extending vertically from its position when inoperative, said means including a lever having one end connected with the chute, a second lever pivotally mounted at its inner end, a link pivotally connecting the outer ends 110 of the levers, a driven shaft, a crank connected with the shaft, and a link connecting the outer end of the crank and the outer end of the second lever, whereby the crank swings the second lever on its pivot, as the shaft is rotated, which in turn swings the first lever through its connection therewith to move the chute from one position to another. 115

2. In a material mixing machine including a discharge chute and means mounting the same for movement from an inoperative position with its receiving end lowermost, said chute tending to move by gravity to elevate and shift its receiving end, means for swinging the chute from its inoperative position to 120

- an operative position with its receiving end uppermost and inward of a line extending medially from its position when inoperative, said means including a lever having one end 5 connected with the chute, a second lever pivotally mounted at its inner end, a link pivotally connecting the outer ends of the levers, a driven shaft, a crank connected with the shaft, a link connecting the outer end of the 10 crank with the second lever, and means for rotating the shaft whereby the crank swings the second lever on its pivot which in turn swings the first lever through its connection therewith to move the chute from one position 15 to another, said first-mentioned link passing beyond a dead center of the pivot of the second lever as the chute reaches its inoperative position whereby movement of the chute by gravity to an intermediate position 20 is prevented.
3. In a material mixing machine having a discharge chute movable to and from operative position, means for moving the chute and including a lever having one end connected 25 with the chute, a second pivotally mounted lever, a link connecting the free ends of the levers, a driven shaft, an arm movable with the shaft, a second link connecting the arm with the second lever, and means for rotating the 30 shaft whereby the arm swings the second lever on its pivot which in turn swings the first lever through its connection therewith to move the chute from one position to another, the connection between the first mentioned 35 link and the second lever passing beyond a dead center of the pivot of said second lever as the chute reaches either limit of movement to prevent movement of the chute by gravity.
4. In a material mixing machine, means for 40 moving the chute from one position to the other and including a member fixed with respect to the chute, a pivotally mounted lever, a link connecting said member and the pivotally mounted lever, an actuating member, and a second link connecting the actuating member with the pivotally mounted lever adjacent its connection with the first mentioned link, whereby movement of the actuating 45 member rocks the pivotally mounted lever to move the chute from one position to the other, the connection of the first mentioned link with the pivotally mounted lever passing beyond dead center at both limits of movement 50 of the chute to releasably secure the same in such position.

In testimony whereof I have hereunto affixed my signature.

ADOLPH W. RYBECK.
